UNITED STATES PATENT OFFICE.

THOMAS L. SMITH, OF MILWAUKEE, WISCONSIN, ASSIGNOR TO THE T. L. SMITH COMPANY, OF MILWAUKEE, WISCONSIN, A CORPORATION OF WISCONSIN.

MIXING-MACHINE.

No. 880,248.

Specification of Letters Patent.

Patented Feb. 25, 1908.

Application filed December 23, 1904. Serial No. 238,064.

To all whom it may concern:

Be it known that I, THOMAS L. SMITH, residing in Milwaukee, in the county of Milwaukee and State of Wisconsin, have invented new and useful Improvements in Mixing-Machines, of which the following is a description, reference being had to the accompanying drawings, which are a part of this specification.

10 My invention has relation to improvements in means for mixing concrete, or the like.

The objects of the invention are to rapidly and effectively mix the ingredients together 15 for forming the concrete mortar, or the like, without at the same time presenting any interior surfaces which are subject to being clogged up by the ingredients, and without subjecting the parts of the mechanism to 20 undue jarring, the construction being such that the receptacle is rotated smoothly and with but almost an imperceptible amount of jarring and hence with but very little strain upon the parts, thereby prolonging the life- 25 time of the machine; to provide a quick and effective discharge of the mixed up batch; to provide for permitting of the ready dumping of the discharged batch into wheelbarrows, or other suitable carrying devices; to dispense 30 with the use of mixing blades, and thereby prevent clogging, and at the same time secure all the advantages of a cubical mixing receptacle devoid of interior mixing blades, without the attendant disadvantages of the 35 cubical form of receptacle, which, in practice, has been found subject to undue jarring and strain on the parts; and to provide a mixing machine which is not only simple in construction, but which is also exceedingly 40 economical in cost.

With the above primary objects, and other incidental objects, in view, the invention consists of the devices and parts, or their equivalents, as hereinafter set forth.

45 In the accompanying drawings, Figure 1 is a side view, with the receptacle in section and other parts broken away; Fig. 2 is a view of the discharging end of the machine, parts broken away; Fig. 3 is a section on the 50 line 3-3 of Fig. 1; Fig. 4 is a horizontal central section of the receptacle; Fig. 5 is a sectional view taken on a plane through the rim or periphery of the receptacle, and illustrating a modified form of the interior agitating devices; Fig. 6 is a section through the

form of receptacle shown in Fig. 5, the section being taken on a plane at right angles to the plane of the section of Fig. 5; and Fig. 7 is a section of a fragment of a receptacle provided with another modified form of agitating devices.

Referring to the drawings, the numeral 7 indicates a suitable supporting frame work, above the base of which the mixing receptacle 8, preferably, although not necessarily, 65 in some embodiments of my invention, of cylindrical form, is supported. The receptacle is rotatably supported on rolls 9, which are loosely mounted on shafts 10, which shafts have their bearings in the frame work. 70 These rolls engage annular rails 11, 11 at opposite edges of the periphery of the receptacle, said rails provided with flanges 12 projecting at right angles thereto, and against which rails the inner sides of the rolls bear, 75 the said flanges of the rails preventing side- wise movement of the receptacle. The receptacle is positively driven or rotated by means of two pinions 13, 13, mounted on a transverse shaft 14, the said pinions engag- 80 ing annular racks 15, 15 arranged around the periphery of the receptacle. These racks are adjacent to, and occupy an inner position with relation to, the rails 11. As a matter of convenience in construction, each 85 rail 11 and annular rack 15 may be formed on a single annulus or band surrounding the outer edge of the periphery of the receptacle, as shown in the drawings. The transverse shaft 14 is mounted in suitable bearings carried by the frame work, and the said shaft at one end has mounted fast thereon a belt wheel 16, around which a belt (not shown) extending from any suitable source of power 90 may pass. One of the head pieces of the 95 receptacle is provided with an opening 17 through which the materials to be mixed may be fed into the receptacle, or in lieu of the materials being fed directly through the opening, a hopper, hereinafter referred to 100 and having a spout leading through the opening, may be provided. The opposite head piece is provided with an opening 18, for the accommodation of the discharging mechanism.

105 As herein before stated, the interior of the receptacle is devoid of mixing blades, and in lieu of this I have adopted a peculiar construction for the interior of the receptacle, consisting of agitating devices or walls set 110

at each end of the receptacle, and extending from the respective head pieces to the rim of the receptacle at an angle to the axis of rotation of the receptacle, and on a decline 5 longitudinally from the head piece to the rim, and which devices act as deflectors and create crosswise movement of the contained material. In other words, the broad idea of the invention may be said to comprehend, 10 in combination with the rim or periphery of a mixing receptacle, of an agitating device or devices extending from the head or heads of the receptacle to the rim of said receptacle in the direction of the length of the 15 axis of rotation but at an angle thereto, said wall having its outer edge joined to one of the head pieces of the receptacle, and its inner edge joined to the rim and extending to an intermediate point of said rim, whereby 20 the space outside or back of the wall is completely cut off from the receptacle.

Referring particularly to the construction of this portion of my invention, and to the form illustrated on Sheets 1 and 2 of the 25 drawings, the numerals 19 and 20 indicate plane inclined surfaces which extend from the inner side of the head piece on the charging side of the machine to the inner side of the periphery of the receptacle in divergent 30 lines, and 21 and 22, respectively, the plane surfaces which extend from the inner side of the head piece on the discharging side of the machine to the inner side of the periphery of the receptacle in divergent lines. 35 The inner edges of these several plane surfaces where they meet the periphery or rim of the receptacle necessarily take a rounded form, and the innermost points of these rounded edges extend to the center, or approximately 40 the center, of the periphery.

From the construction thus far explained, it will be evident that when the receptacle is rotated, the plane surfaces will effect a thorough agitation and mixing of the materials in the receptacle, the said plane surfaces necessarily causing a back and forth crosswise movement of the contained materials, and the receptacle, at the same time, causing a turning movement to be given to 45 the materials. It will also be noted that the lines of the several plane surfaces on one side, if continued outside of the receptacle, would intersect the axial line at the same point. These several plane surfaces act as 50 deflectors, that is to say, the material that falls on one surface is deflected from the nearest head toward the opposite head, and the deflection from one side is opposite to the deflection from the opposite side, so that an 55 alternate crosswise movement is effected.

As before stated, if desired, the materials to be mixed can be fed into the receptacle directly through the opening 17. I prefer, however, to provide a feed hopper 23 supported adjacent to the outer side of the

charging end of the receptacle and provided with a spout 24 leading into the opening 17. The feed of the materials from the hopper to the spout and thence into the receptacle may be governed by means of a door or gate 70 25 which controls the opening between the hopper and the spout, and is slideable in angular guide ways 26, 26. The gate is moved up and down in its guide ways so as to effect its opening and closing by means of a 75 lever 27, pivoted at the point 28, and provided with a short arm 29, preferably bent downwardly slightly, and having pivoted to its end a link 30, which link at its lower end is pivoted to the gate. The hopper, in the 80 first place, is filled with the required amount of the materials to be mixed. When so filled, the gate is opened, and these materials are thereby permitted to pass into the receptacle. The gate is again closed, and during the mixing operation the hopper is 85 refilled with the next charge of the required amount, and which charge is likewise, by the opening of the gate, permitted to pass into the receptacle, after the first charge has been 90 thoroughly mixed and discharged from said receptacle.

I also provide in connection with my invention an improved form of discharging mechanism. This discharging mechanism 95 contemplates, in connection with certain mechanism to be described, the employment within the receptacle of a scoop or bucket, or preferably a plurality of scoops or buckets, and I have found by experience that two 100 of the scoops or buckets referred to, indicated by the numerals 31 and 32, respectively, and extending inwardly from the opposite head pieces of the receptacle, secure most advantageous results. 105

It will be understood that the receptacle rotates in the direction indicated by the arrow in Fig. 3. When, in the rotation of the receptacle, the bucket 31 shown in Fig. 3 reaches a lower position, it will begin to 110 scoop up the material, and as it travels upwardly from this lower position, as indicated by the position of the bucket 32 in Fig. 3, it will elevate or lift the material scooped up thereby, and in view of the fact that each 115 bucket is on a decline toward the discharge end of the machine, the material contained within the bucket slides down toward said discharge end of the receptacle. When the scoop or bucket reaches a certain height in 120 its travel upwardly, one of its longitudinal edges will be on a decline and the material within the scoop or bucket will then slide out of the same, and be caught in an upwardly inclined trough 33. Of course, when the 125 scoop or bucket is brought to a still higher position by the rotation of the receptacle, the full contents of said scoop or bucket is at once emptied into the trough. The trough 33 leads to a discharge hopper or receptacle 130

34, and the outer end of said trough is open so as to discharge directly into the hopper. The hopper is sufficiently elevated to permit a wheelbarrow, or other carrying device, to be run therebeneath, and the bottom of the hopper is provided with a discharge opening which may be controlled by any suitable form of gate, or other closure. I prefer to provide a closure consisting of the gate portion 35, and the arms 36 extending upwardly from opposite ends of the gate and straddling the sides of the hopper 34, and pivoted to said sides of the hopper at the points 37. The gate is preferably struck on an arc of a circle differing slightly from an arc described from the pivot points 37 as a center, whereby a more tight closure is effected than would be the case if the gate were either flat, or struck from the arc of a circle corresponding to an arc described from the pivot points 37. The gate is preferably provided with a handle 38, for convenience in swinging it to an open or closed position.

It will of course be understood that during the mixing operation it is not desirable that the trough 33 should extend through the opening 18 into the receptacle, inasmuch as if it did so extend, the materials or ingredients under process of being mixed would be continually dumped by the buckets into the hopper and thereby interfere with an effective mixing operation. I therefore provide means for readily withdrawing the said trough from the opening during the mixing operation, and inserting the same into the said opening during the mixing operation. The preferred means for this purpose are illustrated in Figs. 1 & 2 of the drawings. Referring to this mechanism, a carriage is provided which is adapted to travel along the top edges of the hopper 34. This carriage preferably consists of the top pieces 39, 39 which, at their outer edges, rest upon angular rails 40, 40, said rails forming a track for the travel of the carriage. The extreme outer edges of the top pieces are bent into hook form, and the horizontal members of these hooks extend beneath the horizontal flanges of the angular rails 40, and hence retain the carriage against upward removal from the said rails 40. From the upper side of the top pieces 39 extend standards 41 & 42. The outer pair of standards 42 are connected by a transverse connecting piece 43, which transverse piece not only serves as a handle for causing the backward and forward travel of the carriage, but also serves to connect the two top pieces of the carriage. The discharge trough 33 is connected to the carriage by means of arms 44 which extend outwardly between the two pair of standards 41 & 42, and are connected to said standards in any desirable manner. When the carriage is moved backward and forward, the trough 33, by reason of the connection of said trough to

the carriage, is necessarily moved with the carriage. In the movement of the trough it preferably rides on rollers 45 at the outer end of said trough. These rollers travel on the rails 40.

In practice, under certain conditions, it will be desirable to vary or adjust the inclination of the trough 33. This may be accomplished in various ways, but I prefer to effect the adjustment by providing the two pair of standards 41 and 42 with curved slots 46 extending in the direction of the length of said standards. Through these slots are passed small screws 47, which screws enter and have threaded engagement with the arms 44 of the carriage. It is obvious that by loosening the screws the trough 33 may be turned on the rollers 45 as pivots, so as to either raise or lower the inner end of said trough to suit requirements. In order to limit the outward travel of the carriage, I provide stop pins or lugs 48, projecting laterally from the rails 40, with which depending fingers 48' at the front end of the carriage are adapted to contact.

It will be noticed that the scoops or shovels 31-32 are of peculiar construction, that is to say, they are on a decline from their inner ends towards and to the outer ends thereof, and at said outer ends the concavity is somewhat more depressed, or is deeper than at any other point thereof as indicated by the numeral 49. As each scoop or bucket is on a decline toward the discharge end of the receptacle, the material scooped up by a bucket necessarily slides down toward that end of said bucket which connects with the head of the receptacle at the discharge end of said receptacle, and for this reason it is important that this end of the scoop or bucket be deeper than other portions thereof. The inclining of a scoop or bucket in the direction described is to bring the principal point of discharge of each bucket, and which is the depressed portion, adjacent to the end piece or head at the discharge end of the receptacle, so as to avoid the necessity of projecting the trough into the receptacle to any considerable distance.

It will be further noted that the bordering edges of the charging and discharging openings of the opposite head pieces are flanged or curved outwardly as indicated by the numerals 50, 50. This prevents the spilling outwardly of the ingredients during the mixing operation, the flanged edges forming deflectors which act to deflect the spilling materials inwardly.

In Figs. 5 and 6 of the drawings, I show a modified form of the agitating or mixing devices, in which the acting exposed face of each device is of a substantially pyramidal form, the said devices, however, extending from the respective head pieces of the receptacle to the periphery of said receptacle at angles

to the axis of rotation of the receptacle and on a decline longitudinally from the head piece to the rim, the same as in the form of construction illustrated upon Sheets 1 and 2 of the drawings. The agitating devices of the Figs. 5 and 6 form of construction which extend from the charging end of the receptacle, are indicated by the numerals 51, and those which extend from the discharging end 10 of the receptacle by the numeral 52. This modified form of agitating devices is a desirable form of construction, inasmuch as the said devices do not present sharp or acute angles liable to be clogged by the materials being mixed, at the points of joinder with the head pieces.

In Fig. 7 is shown another modified form of agitating devices in which the acting exposed face or surface of each device is of a 20 rounded or convex form. The agitating devices of the Fig. 7 form of construction which project from the charging end of the machine are indicated by the numeral 53, and those which project from the discharging end of 25 the machine by the numeral 54.

In both the forms illustrated on Sheet 2 it is preferable that three of the scoops or buckets (31 and 32) project from each of the 30 respective head pieces of the receptacle. Also in both of these forms of construction discharging mechanism similar to that illustrated on Sheet 1 of the drawings may be employed, or any other suitable provision may be made for effecting the discharge of 35 the mixed materials from the receptacle.

When it is desired to effect the mixing operation, the discharging trough 33, where this is used, is adjusted outwardly as herein before explained. The materials to be 40 mixed are then poured into the hopper 23, and from said hopper pass into the interior of the receptacle. During and after the charging operation, power is applied to the shaft 14 so as to effect the rotation thereof. 45 Shaft 11 acts to rotate the receptacle through the gearing herein before described, and this rotation of the receptacle, through the medium of the agitating devices, causes a thorough agitation and mixing of the contained 50 ingredients, by reason of the back and forth crosswise movement imparted thereto, and at the same time the rotation of the receptacle causes a turning movement to be imparted to the ingredients, as herein before alluded 55 to. After the mixing operation is completed, the discharging trough is adjusted inwardly through the opening 18, and with the continued rotation of the receptacle the mixed batch is dumped into the trough from the 60 buckets 31 and 32. When the discharging hopper 34, shown in Fig. 1, is employed, the discharged material is deposited in said hopper, and may be removed therefrom by swinging the gate 35 to an open position so 65 as to permit the material to empty into a

wheelbarrow, or other carrying device, beneath the discharge opening of the hopper. This construction possesses the advantage of stopping the discharge whenever for any reason this is desirable, by closing the gate 35. 70 It is particularly desirable to stop the discharge in the period of time between wheeling a filled barrow from beneath the discharge opening of the hopper and wheeling another barrow to be filled beneath said 75 opening.

While I prefer to make the receptacle of cylindrical form, yet I do not wish to be understood as limiting myself thereto, inasmuch as the rim of said receptacle may be of 80 any desirable shape, such, for instance, as square, rectangular, octagonal, etc., so long as opposite head pieces are provided and a connecting rim employed in order to furnish provision for an agitating device or devices 85 extending from the head piece or pieces to the rim, in the manner herein before fully described.

Each of the agitating devices herein before specifically described consists, preferably, of 90 a plane, although the surfaces of each of said devices may be spherical, or may be conical, or may consist of two planes, or may be rounded. Furthermore, these surfaces which form the agitating devices are so arranged as 95 to constitute a line of division between the interior of the receptacle and the space on the outside of the plane or surfaces constituting the agitating devices or walls, there being no communication between the interior of the 100 receptacle and the space back or outside of these plane surfaces, or, in other words, the space confined between the agitating wall and the portions of the rim and head piece which each agitating wall connects. It will 105 be understood, however, that if in the process of manufacturing the receptacle it is preferred to leave off entirely the portions of the rim and head piece which each agitating wall connects, this of course would be permissible 110 under the spirit and scope of my invention.

What I claim as my invention is:

1. In a mixing machine, in combination with a mixing receptacle having head pieces and a connecting rim and also having a discharge opening and an interior wall independent of and extending from the head piece to the rim in the direction of the length of the axis of rotation but at an angle thereto, said wall having its outer edge joined to one 120 of the head pieces of the receptacle, and its inwardly extending edge joined to the rim and extending to an intermediate point of said rim, whereby the space outside or back of the wall is completely cut off from the interior of the receptacle, of means for charging the receptacle, and means for rotating the receptacle.

2. In a mixing machine, in combination with a mixing receptacle having head pieces 130

- and a connecting rim and also having a discharge opening and interior walls independent of and extending, respectively, from the opposite head pieces to the rim in the direction of the length of the axis of rotation but at an angle thereto, each wall having its outer edge joined to one of the head pieces of the receptacle, and its inwardly extending edge joined to the rim and extending to an intermediate point of said rim, whereby the spaces outside or back of the walls are completely cut off from the interior of the receptacle, of means for charging the receptacle, and means for rotating the receptacle.
- 15 3. In a mixing machine, in combination with a mixing receptacle having head pieces and a connecting rim and also having a discharge opening and interior walls independent of and extending from one of the head pieces to the rim in the direction of the length of the axis of rotation but at an angle thereto, said walls arranged in pairs extending from the head to the rim in divergent lines, and each wall having its outer edge joined to the head piece of the receptacle and its inwardly extending edge joined to the rim and extending to an intermediate point of said rim, whereby the space outside or back of the wall is completely cut off from the interior of the receptacle, of means for charging the receptacle, and means for rotating the receptacle.
- 20 4. In a mixing machine, in combination with a mixing receptacle having head pieces and a connecting rim and also having a discharge opening and interior walls independent of and extending from the head piece to the rim in the direction of the length of the axis of rotation but at an angle thereto, said walls facing each other and extending from the head to the rim in divergent lines, and each wall having its outer edge joined to the head piece of the receptacle, and its inwardly extending edge joined to the rim and extending to an intermediate point of said rim, whereby the space outside or back of the wall is completely cut off from the interior of the receptacle, of means for charging the receptacle, and means for rotating the receptacle.
- 25 5. In a mixing machine, in combination with a mixing receptacle having head pieces and a connecting rim and also having a discharge opening and a plurality of interior walls extending from each head piece to the rim in the direction of the length of the axis of rotation but at an angle thereto, said walls extending from each head piece being arranged in pairs, one pair of said walls extending from one head piece alternating in position to a pair of walls extending from the opposite head piece, of means for charging the receptacle, and means for rotating the receptacle.
- 30 6. In a mixing machine, in combination with a mixing receptacle having head pieces and a connecting rim and also having a discharge opening and a plurality of interior walls extending from each head piece to the rim in the direction of the length of the axis of rotation but at an angle thereto, said walls which extend from each head piece being arranged in pairs and extending from the respective head pieces in divergent lines with respect to the axis of rotation, and one pair of said walls extending from one head piece alternating in position to a pair of walls extending from the opposite head piece, of means for charging the receptacle, and means for rotating said receptacle.
- 35 7. In a mixing machine, the combination of a mixing receptacle provided with a discharge opening, rails extending outwardly from the discharge opening, a carriage adapted to travel on said rails, a trough connected to the carriage and adapted, when the carriage is moved inwardly, to be projected through the discharge opening of the receptacle, and into the receptacle, and, when the carriage is moved outwardly, to be withdrawn through the discharge opening from within the receptacle, means within the receptacle for scooping up the mixed materials and depositing the same in the trough, and means for charging the receptacle.
- 40 8. In a mixing machine, the combination of a mixing receptacle provided with a discharge opening, rails extending outwardly from the discharge opening, a carriage adapted to travel on the rails, a trough connected to the carriage and provided with rollers resting on the rails, said trough adapted when the carriage is moved inwardly to be projected through the discharge opening of the receptacle, and into the receptacle, and, when the carriage is moved outwardly, to be withdrawn through the discharge opening from within the receptacle, means within the receptacle for scooping up the mixed material and depositing the same in the trough, and means for charging the receptacle.
- 45 9. In a mixing machine, the combination of a mixing receptacle provided with a discharge opening, rails extending from the discharge opening, a carriage adapted to travel on the rails, said carriage provided with a projecting upright, said upright having a segmental slot extending in the direction of the length thereof, a trough provided with an outward projection extending across the upright, a screw passing through the slot of the upright and engaging the projection of the trough, said trough, when the carriage is caused to travel inwardly, being projected through the discharge opening and caused to extend into the receptacle, and, when the carriage is moved outwardly, to be withdrawn through the discharge opening from within the receptacle, means within the receptacle for scooping up the mixed material and depositing the same in the trough.

als and depositing the same in the trough, and means for charging the receptacle.

10. In a mixing machine, the combination of a mixing receptacle provided with a discharge opening, a hopper adjacent to the discharge opening of the receptacle, said hopper provided with a discharge opening, a carriage adapted to travel on the upper edges of the hopper, a trough connected to the carriage and so constructed as to discharge into the hopper, and adapted, when the carriage is moved inwardly, to be projected through the discharge opening of the receptacle, and into the receptacle, and, when 15 the carriage is moved outwardly, to be withdrawn through the discharge opening from within the receptacle, means within the receptacle for scooping up the mixed materials and depositing the same in the trough, and 20 means for charging the receptacle.

11. In a mixing machine, the combination of a mixing receptacle provided with a discharge opening, a hopper adjacent to the discharge opening of the receptacle, said 25 hopper provided with a discharge opening, a carriage adapted to travel on the upper edges of the hopper, a trough connected to the carriage and so constructed as to discharge into the hopper, said trough provided at its 30 outer end with rollers adapted to travel on the upper edges of the hopper, and said trough adapted, when the carriage is moved

inwardly, to be projected through the discharge opening of the receptacle, and into the receptacle, and, when the carriage is moved outwardly, to be withdrawn through the discharge opening from within the receptacle, means within the receptacle for scooping up the mixed materials and depositing the same in the trough, and means 40 for rotating the receptacle.

12. In a mixing machine, the combination of a mixing receptacle provided with a discharge opening, rails extending outwardly from the discharge opening, a carriage 45 adapted to travel on the rails, a trough connected to the carriage and extending therefrom at an upward incline, said trough adapted when the carriage is moved inwardly to be projected through the discharge opening of the receptacle, and into the receptacle, and, when the carriage is moved outwardly, to be withdrawn through the discharge opening from within the receptacle, means within the receptacle for scoop- 50 ing up the mixed materials and depositing the same in the trough, and means for charging the receptacle.

In testimony whereof, I affix my signature, in presence of two witnesses.

THOMAS L. SMITH.
